UNITED STATES PATENT OFFICE.

CHARLES W. HALES, OF CHICAGO, ILLINOIS, ASSIGNOR TO GULBRANSEN-DICKINSON COMPANY, OF CHICAGO, ILLINOIS, A CORPORATION OF ILLINOIS.

ADVERTISING DEVICE.

Application filed March 3, 1920. Serial No. 363,033.

To all whom it may concern:

Be it known that I, CHARLES W. HALES, a citizen of the United States, residing at Chicago, in the county of Cook and State 5 of Illinois, have invented a certain new and useful Improvement in Advertising Devices, of which the following is a full, clear, concise, and exact description, reference being had to the accompanying drawings, forming 10 a part of this specification.

This invention relates to advertising devices and has for its primary aim to provide means for bringing individually to the attention of the observer some vitally important feature of the article on display or being advertised, and is designed also as an improvement over Patent No. 1,288,759, granted to T. B. Thompson, December 24, 1918.

20 Another object of my invention is to provide means for advertising player pianos, particularly to emphasize the ease and facility with which the piano may be played by employing, in connection with the pedal mechanism thereof, means representing the application of the relatively light force to the pedal.

Another object of my invention is to provide, in conjunction with the above, means for continuously operating the piano, and the pedal mechanism thereof, so as to convey to the observer the idea that the same is being operated by the application of a light force, such as would be applied by a child.

35 A further object of my invention is to provide means for continuously operating the piano, reversing the music roll and operating the pedal mechanism in the exposed or projected position. I preferably employ a figure representing that of a child with one hand on the pedal, and I provide means for connecting that hand to the pedal.

40 A still further object of my invention is to provide an improved mounting for the prime mover, in this case an electric motor, which is mounted inside the piano case.

While I shall describe a particular form of my invention and refer to the same as an advertising or display device, I do not limit myself to the application of the invention as set forth, as the scope of adaptability of the device is not limited to that shown.

Other objects and advantages of my invention will appear from the following de-

tail description and the claims, taken in 55 connection with the accompanying drawings, in which:

Figure 1 is a front elevation of a piano showing my invention applied thereto, portions of the piano being broken away; 60

Figure 2 is a fragmentary plan view of the same;

Figure 3 is an enlarged front elevation of the transmission shifting device;

Figure 4 is a side elevation of the same; 65

Figure 5 is a detail view of the pedal connection; and

Figure 6 is an enlarged side elevation of the motor mounting.

Referring in detail to the embodiment of 70 my invention as disclosed, 10 designates a piano casing which houses the piano action and player mechanism. In the form of the invention shown, a piano of the upright type has been disclosed, but it will be readily 75 appreciated as this description proceeds that the invention is not limited in application to this style of piano. The casing 10 is composed of the sounding board or back wall 11, base board 12 and end walls 13 80 and 14. The keyboard 15 extends outwardly from the piano casing, as in the conventional form of upright piano and is supported by columns 16 and 17, at either end of the piano. The usual frame 18 is mounted on the sounding board 11 and carries the strings 19.

A roll box 20 is shown, in which the rollers 21 and 22 are adapted to be mounted, carrying the music web 23 which passes 90 over the tracker bar 24. The tracker bar is provided with the usual openings 24' communicating with the pneumatics, not shown, and is also provided with an additional opening 25, for a purpose which will 95 hereinafter appear. The music web 23 is provided with a series of perforations in the conventional manner and is also provided with a series of perforations 25' at or near each end of the music web, which openings 100 25' are adapted to register with the additional openings 25 in the tracker bar for a purpose which will appear hereinafter. The roll box has not been shown in its proper position for obvious reasons.

105 The usual feeder bellows 26 and 27 are suspended from the block 28 within the piano casing and below the keyboard 15,

the same communicating with reservoirs 29 and 30. The pedal structure may comprise a frame 31 mounted on arms 32 pivoted at 33 within the piano casing and carrying a pair of pedals 34 and 35 pivoted at their outer ends on said frame 31 and capable of vertical movement thereon. The frame is adapted to be folded into the piano casing when not in use. The pedals 34 and 35 are connected to the lower ends of the movable leaves of the feeder bellows 26 and 27 in any suitable manner.

My invention consists essentially in means for oscillating one or both of the pedals, in applying a figure, such as the representation of a child with one hand on one of the pedals, and automatic means for rewinding the music roll at either end of its travel so that the piano will continuously play and the idea will be conveyed to the observer that the child is operating the piano.

The figure or representation of a child is designated 36, the child being represented as on its knees with the left hand 37 beneath the pedal frame and the right hand 38 resting upon the pedal 35 at the upper end thereof. The hand 38 is connected to the pedal in a manner which will be described later, and is pivoted to the body of the figure at 36'.

I provide means for driving the pedal 35, this means consisting of an electric motor 39 mounted on a base 40 in a manner which will be described in detail later. The motor is connected by a belt 41 to a pulley 42 carried on a shaft 43 mounted in a housing 44. The housing contains a worm mounted on said shaft 43, which worm engages with a suitable worm gear carried by a shaft 45, the worm and worm gear not being shown, as the same do not necessarily enter into the invention. One free end of the shaft 45 carries a crank 46 which is engaged with a link 47, which link is in turn connected at 48 to a clamp 49 which engages the upper end of the pedal 35. The clamp is made in two parts connected together by a bolt 50. One of the parts of the clamp 49 is provided with an apertured lug 51 through which a bolt 52 is engaged, said bolt being carried by the hand 38 of the figure 36. This structure is best shown in Figure 5. It will be apparent that when the electric motor 39 is energized the pedal 35 will be oscillated vertically, and its motion will be transmitted to the feeder bellows 27, which in turn will operate the player mechanism of the piano.

It will be readily seen that while the pedal is oscillating vertically the child's hand will rise and fall with the pedal and thus convey the impression that the child is playing the piano.

At 54 I have shown the shifting lever which usually projects in front of the key-

board for manual shifting and reversing of the roll transmission (not shown). In the present application of my improved automatic shift I make no alterations in the conventional form of shifting mechanism, but merely connect a rod 55 to the lever 56 carried by the inner end of the shaft on which said lever 54 is mounted. The rod 55 is coupled by means of an adjustable clamp 57 to a second rod 58, which is in turn connected to the automatic shifting mechanism of my invention, best shown in Figures 3 and 4.

The automatic shifting mechanism hereinbefore mentioned, preferably consists of a block or support 59 made up of laminations of wood or the like in accordance with the general practice in constructing the parts of pianos and provided with a head portion 60 through which a pair of screws 61 pass and engage in the piano casing beneath the keyboard. The upper end of the block 59 and the head member 60 abut one of the stringers 62 of the piano structure.

Mounted on the front face of the block 59 is a wooden disk 63 arranged for rotation on a screw 64 engaging in the block 59. A suitable washer 65 may be interposed between the rear face of the disk 63 and the front face of the block 59 for an obvious purpose. Guiding blocks 66 and 67 are mounted on the front face of the block 59 and are provided with registering slots 68 and 69. A flat bar 70 is mounted in the slots 68 and 69 and adapted for reciprocating movement therein, said bar having the upper end thereof enlarged and provided with a notch 71 adapted to engage successively with one of the four pins 72, 73, 74, and 75, carried by the disk 63. The free end of the rod 58 is formed with an eye 76 which engages over a crank screw 77 carried by the disk 63, a nut 78 on said screw maintaining the eye of the rod in abutment with the head of the screw. The flat bar 70 is prevented from dislodgment from the slot 69, and yet permitted slight oscillation therein by means of a pair of pins 79 which pass through said slot on either side of said bar. The bar 70 is fulcrumed as at 80, to a rod 81, which in turn is connected at 82 to the movable leaf 83 of a pneumatic 84. The pneumatic 84 is provided with the usual valve block 85 in which is contained the valve mechanism, the valve chamber communicating by means of a tube 86 with the feeder bellows reservoirs and with the opening 25 in the tracker bar 24 referred to hereinbefore.

The rod 81 is continued beyond the connection of the same to the movable leaf 83 and carries a weight 87 for insuring positive operation of the shafting mechanism.

The enlarged upper end of the bar 70 is provided with an inclined edge 88, which

is adapted to ride upon the adjacent pin in the disc 63, in this case the pin 72, when said bar is elevated. The lower end of the bar 70 is provided with an extension 89 to 5 which a flat bar 90 is riveted, as at 91. The free end of the flat bar 90 carries a weight 92. This weight acting through the bar 90, and fulcrum 80, tends to maintain the bar 70 in contact with the pins in the disc 10 63 as the same is rotated.

A resilient rod 93 is carried by the blocks 66 and 67, the lower free end of the rod 93 being embedded in the block 67 and the upper end of the rod engaging the peripheral 15 surface of the disc 63. The rod passes through a suitable slot 94 in the block 66, a pin 95 in the block 59 serving to maintain the rod 93 under tension in engagement with the peripheral surface of the disc 63. This 20 rod serves to prevent reverse rotation of the disk and also serves to dampen the rotation of the same.

The pneumatic 84 depends for its operation upon the vacuum system familiar to 25 those in the art and employed in most player pianos for operating the player mechanism pneumatics which strike the notes and a detail description of the same is therefore not thought to be necessary.

30 The operation of the roll reversing mechanism just described is as follows: Assuming, for convenience in describing, that the parts as shown in Figures 1, 3 and 4 are in the position during the playing of the roll. As 35 soon as the roll has been played the series of openings 25' at the end thereof, which correspond to the openings at the beginning of the web, register with the opening 25 in the tracker board. This causes a collapse of the 40 pneumatic 84 which imparts vertical movement to the rod 81 and bar 70, which in turn causes the upper enlarged end of the latter to ride over the pin 72 until the notch 71 engages said pin. As soon as the openings in 45 the music web pass the opening 25 in the tracker bar and the same is closed the suction on the pneumatic 84 is released and the lower leaf thereof drops, together with the rod 81 under the action of the weight 87 and 50 also under the action of the weight 92. This gravitation of the rod 81 is imparted to the bar 70, which in turn rotates the disk 63 through approximately 90 degrees, which reciprocates the rod 58 and throws the transmission into reverse for rewinding. The 55 above consumes two motions of the bar 70, one up and one down. Now, as the roll is rewound the perforations in the web will again for an instant register with the opening 60 in the tracker bar, which will cause another reciprocation of the bar 70 and a partial rotation of the disk 63, but this rotation is so slight that the motion imparted to the rod 58 is not sufficient to disengage the gears 65 of the transmission. After the roll is re-

wound the series of perforations in the music web at the beginning of the roll again register with the opening in the tracker bar which causes a collapse of the pneumatic 84. As soon as the series of perforations passes 70 the opening in the tracker bar the pneumatic is released and the rod 81 and bar 70 again gravitate to rotate the disk 63 through an angle of substantially 90 degrees, sufficient to cause the transmission to shift from 75 rewinding to playing engagement. When the roll starts to play the series of perforations will again register with the opening in the tracker bar and another reciprocation of the bar 70 will be had, but the movement imparted by the bar to the disk 63 is not sufficient to disengage the gears of the transmission. Thus it will be seen that for one playing of the music roll four distinct movements of the bar 70 are produced, two of 80 these motions being "live" and the other two "dead." I desire to lay particular stress upon the step by step movement employed in shifting the transmission, as after considerable experiment this has been found to be a very positive and sure method of shifting the gears of the transmission. The extreme simplicity of the shifting mechanism does away with ratchets or pawls or the like by 85 using two "live" and two "dead" movements 90 of the shifting bar.

95 Referring now to Figure 6, wherein an improved mounting for the electric motor is best shown, I provide a base hereinbefore designated 40, the base 40 being placed within the piano casing as shown in Figure 2 and having an abutment 41' on the end thereof toward the object being driven by the motor. The mounting of the motor consists of two frames, or more if necessary, which are identical in construction and shape and one only will therefore be described. The frame is designated 97 and preferably comprises a flat bar having the central portion thereof formed to provide a raised portion 98 to 100 which the motor base 99 is secured by bolts 105. In the present instance two frames 110 have been provided.

115 The frame 97 is provided with feet portions 101 and 102, the foot portion 101 having an upturned end 103 and being adapted to receive a clamping bar 104 which extends entirely across the base 40, screws 105 engaging through said clamp 104 into the base 40 to secure the clamp. A rubber packing 106 is interposed between the clamp 104, abutment 41' and base 40, and said foot member 101, so that there is no actual metal contact between the motor and the supporting base. The foot portions 102 of the frame 120 members rest upon rubber pads 107. Thus it will be seen that the motor is securely mounted on the base, the free ends of the frame members being left free in order to 125 allow for any unevenness that may be in the 130

ject connected to one of said foot controlled pedals.

14. In combination, a device having a tracker bar over which sheet music is adapted to track, means for reversing the direction of travel of the sheet music, a pneumatic element mechanically connected with said means, and an object positioned adjacent the device for indicating the manner of 10 operating the same, said object being connected to and operated by said device.

15. In combination, a tracker bar having an opening therein adapted to register with perforations in a music sheet, a transmission mechanism governing the direction of 15 travel of the music sheet over the tracker

bar, a reciprocating member connected with said transmission mechanism, a device having progressive movement at the other end of the reciprocating member for imparting 20 movement thereto, means actuated in accordance with the registering of said tracker bar opening with said sheet perforations for actuating said device, and a representation of an instructor for indicating the ease and 25 mode of operating the device, said representation being connected to and operated by the device.

In witness whereof I hereunto subscribe my name this 27 day of Feb., 1920.

CHAS. W. HALES.

Certificate of Correction.

It is hereby certified that the assignee in Letters Patent No. 1,504,552, granted August 12, 1924, upon the application of Charles W. Hales, of Chicago, Illinois, for an improvement in "Advertising Devices," was erroneously described and specified as "Gulbransen-Dickinson Company, of Chicago, Illinois, a corporation of Illinois," whereas said assignee should have been described and specified as *Gulbransen Company, of Chicago, Illinois, a corporation of Illinois*, as shown by the records of assignments in this office; and that the said Letters Patent should be read with this correction therein that the same may conform to the record of the case in the Patent Office.

Signed and sealed this 28th day of October, A. D. 1924.

[SEAL.]

KARL FENNING,
Acting Commissioner of Patents.
